UNITED STATES PATENT OFFICE.

OTTO KARL REINHARDT, OF JAMAICA, NEW YORK, ASSIGNOR TO YALE ELECTRIC CORPORATION, A CORPORATION OF NEW YORK.

BOBBIN-MAKING MACHINE.

Application filed December 18, 1922. Serial No. 607,575.

To all whom it may concern:

Be it known that I, OTTO KARL REINHARDT, a citizen of Germany (having taken out first United States papers), and a resident of Jamaica, county of Queens, State of New York, have invented certain new and useful Improvements in Bobbin-Making Machines, of which the following is a specification.

10 This invention relates to bobbin making machines adapted for the production of bobbins employed in the manufacture of dry cells.

An important object of the invention is 15 to provide, in a machine of the character mentioned, a generally improved means to facilitate speed and accuracy in measuring the carbonaceous mix or depolarizing mass in combination with cooperative mechanism 20 for intimately compressing such mix into a relatively compact mass.

A further object of the invention is to provide in the above mentioned combination a 25 means for introducing an electrode into the intimately compressed mass, and thereafter imparting to the bobbin a final compression to more intimately and firmly unite the bobbin components prior to their being ejected from the machine.

30 Other objects and certain advantages of the invention will become apparent from the following description when taken in connection with the accompanying drawings in which—

35 Figure 1 is a front elevation of the machine embodying my invention.

Figure 2 is a vertical sectional view taken on line 2—2 of Figure 1.

Figure 3 is an end elevation of the 40 machine viewed from the left in Figure 1.

Figure 4 is a horizontal sectional view taken on line 4—4 of Figure 1.

Figure 5 is a vertical sectional view taken on line 5—5 of Figure 1.

45 Figure 6 is a horizontal sectional view taken on line 6—6 of Figure 5.

Figure 7 is a fragmental rear elevation of the machine.

Figure 8 is a sectional view taken on line 50 8—8 of Figure 1.

Figure 9 is a view similar to that of Figure 8 showing the several elements thereof in different operative positions.

55 Figure 10 is a sectional view taken on line 10—10 of Figure 1.

Figure 11 is a sectional view taken on line 11—11 of Figure 3.

Figure 12 is a detail view showing in elevation a feed hopper agitating mechanism.

60

In the drawings wherein for the purpose of illustration is shown what I consider the preferred form of my invention, the numeral 5 indicates, as a whole, a frame or pedestal which includes a pair of vertically disposed supporting brackets 6, adapted for the reception of a box-like container 7, into which the depolarizing material is deposited and from which it is transferred to an endless conveying mechanism indicated as a 65 whole by the numeral 8, and hereinafter more particularly described. The main frame of the machine is indicated as a whole by the numeral 9, and comprises a base 10, adapted to cooperate with the upper portion 70 11 thereof to support the various combination of cooperative elements hereinafter more particularly described. To the upper portion of the frame 11 there is suitably journaled a crank shaft 12 adapted to be 75 driven from an appropriate source of power, not shown, through a belt 13 and a pulley 14, the shaft 12 being provided, intermediate its ends, with a crank 15. To this crank there is suitably connected a pitman 16, operatively connected to a cross head 17, adapted to reciprocate vertically within guides 18, connected to the upper portion of the frame. The cross head 17 is provided with a spring 80 retaining chamber 19, into which is fitted a yieldable plunger 20 adapted to be adjusted by means of a nut 21, under the influence of a compression spring 22 carried within the chamber 19 and engaging the head 23 of the plunger to which is suitably connected a 85 depending tamper 24, the function of which will be more readily appreciated when considering the following description.

90 In proximity to the cross head 17 there is arranged a reciprocating compression head 100 25, which comprises a plurality of radially disposed arms 26, 27, 28, and 29. This compression head is operated through the instrumentality of a vertically movable shaft 31, arranged to reciprocate within a journal 32, suitably connected to the frame 9. The vertically movable shaft is, at its lower end, connected to a cross head 33, adapted to operate within a guide 34, supported by means of a bracket 35, which is connected to the 105 110

base 10. Reciprocatory movement is imparted to the cross head 33 through the instrumentality of a link 36 pivotally connected thereto, and in turn pivotally connected to a bell crank lever 37 supported by the frame 9. This bell crank lever, at one end, is provided with a roller 38, cooperating with a cam 39, suitably connected to a drive shaft 40 journaled to the frame 9, and 10 driven through the instrumentality of a sprocket 41 geared to a shaft 42 and operatively connected, by means of an interposed sprocket chain 43 with a sprocket 44 secured to the shaft 42. The shaft 42 together with 15 the several sprockets derives its power of rotation from the shaft 12 through the instrumentality of a sprocket wheel 45 suitably connected thereto, and in turn connected by means of a sprocket chain 46 to a 20 sprocket wheel 47, carried by the shaft 42. It will be appreciated that when the shaft 40 is rotated the shaft 31 by reason of the several cooperative elements just described is 25 raised and lowered carrying with it the compression head 25.

The arms 26, 27, 28 and 29 comprising the compression head 25 are provided with plungers 48, 49, 50 and 51, respectively, which are adapted to be adjusted vertically 30 and thereafter locked in their respective adjusted positions by means of lock screws 52. These plungers are adapted to function respectively to slightly compress the carbonaceous or depolarizing material and partially 35 eject the same, insert the carbon electrode, subsequently compress the carbonaceous or depolarizing material, thereby intimately uniting the components of the bobbin and to finally eject the more or less homogeneous 40 mass, their operation in detail being more readily appreciated when considering the several features of the machine hereinafter more particularly described.

Directly beneath the compression head 25 45 and rotating about the vertically reciprocating shaft 31 is arranged an intermittently operated table 53 provided with an elongated bearing sleeve 54 journaled within a suitable bearing 55 appropriately supported 50 by the frame 9. This bearing sleeve 54 in turn is rigidly connected to a clutch sleeve 56 carrying at its upper end a plate or peripheral extension 57, provided with a plurality of notches 58. These notches are 55 adapted to receive a locking dog 59 carried at the end of a rocker arm 60 suitably supported by the frame 9 and adapted to cooperate with a tension spring 60' which functions as a means for retaining the dog 60 either within a given notch 58 or in engagement with the peripheral surface of the plate 57. The dog 59, when positioned within one of the notches 58, positively locks the table 53 in a given position during a predetermined phase in the cycle of operation of 65

the machine but is adapted to be released from the notches 58 successively by means of a release cam 61, carried by a collar 62 loosely mounted upon the sleeve 56, when the sleeve is so moved through the instrumentality of the mechanism presently described as to bring the cam face 63 of the cam 61 into engagement with a depending lug 64, carried by the arm 60. To the collar 62 there is also connected a radially extending arm 65, to which is pivotally connected a pawl 66 adapted to successively engage ratchet teeth 67 carried by a ratchet 68 rigidly connected to the sleeve 56. It will be appreciated that when the arm 65 has reached the limit of its movement in one direction, the plate 57 is brought into such a position as to permit the dog 59 to drop into one of the notches 58, thereby locking the table 53 in a given position in which position it is maintained during a predetermined phase in the cycle of operation of the machine. Upon return movement of the arm 65 in the direction of the arrow shown in Figure 9 the release cam 61 is so moved into engagement with the lug 64 as to move the dog 59 out of the particular notch into which it has been previously seated. Upon disengagement of the dog 59, the pawl 66 will have moved a sufficient distance to engage the next succeeding ratchet tooth 67 and the release cam 61 will also have moved a sufficient distance to maintain the dog 59 retracted a sufficient length of time to prevent its entering the notches 58 at the beginning of the reverse movement of the arm 65. By the time the release cam 61 has moved out of engagement with the lug 64 the plate 57 will have so moved that the dog 59 will engage the peripheral margin of the plate 57, its engagement being maintained until the arm 65 has again reached the limit of its movement in the direction opposite to that indicated by the arrow of Figure 9 at which time the dog 59 is again permitted to enter the next succeeding notch 58. In order to prevent the table 53 from so moving, by reason of its momentum upon the completion of the operating stroke of the arm 65, as to prevent the dog 59 from entering the next succeeding notch 58 I have provided a friction brake indicated as a whole by the numeral 69, and comprising a pair of adjustable bands 70, adapted to frictionally engage a brake disc 71 suitably connected to the elongated bearing 54 and adapted to rotate therewith. The means for driving the intermittently actuated mechanism operating the table 53 and hereinbefore described comprises a cam lever 72 pivotally connected to the frame 9 and provided with a roller 73 adapted to cooperate with a cam 74 carried by the shaft 40, the outer end of the arm 72 being pivotally connected to a

pitman rod 75 operatively connected to the outer end of the arm 65 by means of a toggle or universal joint 76.

The rotatable table 53 hereinbefore mentioned is provided, near its periphery, with a plurality of pockets or openings 77 carrying bushings 78 preferably constructed from wood or other suitable material upon which the carbonaceous or depolarizing material has but little detrimental effect. These bushings are adapted to receive the carbonaceous or depolarizing material from a hopper indicated as a whole by the numeral 79, which material, when first introduced, is tampered or compressed to a predetermined density by the plunger 24. The table 53 is so rotated as to bring the bushing into which the material has previously been introduced into registration with the plunger 48 which functions to exert upon the material a slight compressing influence and at the same time so move the material within the bushing as to cause the same to project slightly below the lower end of the bushing. Upon the next intermittent movement of the table 53 the bushing carrying the previously compressed material is brought into registration with the plunger 49 which functions cooperatively with a selective feeding mechanism indicated as a whole by the numeral 80, and hereinafter more particularly described, to insert or imbed a carbon electrode into the material. Subsequent to the introduction of the electrode into the depolarizing material, the table 53 is again, after two successive operations, so moved as to bring the pocket carrying the compressed material having the electrode introduced thereinto, into registration with the plunger 50 which, as most clearly shown in Figure 5, is provided with a central passage 81 adapted to receive the upper end of the electrode when the plunger is moved into engagement with the surrounding material to exert thereupon a final compressing influence thereby more intimately uniting the carbon and depolarizing mass into a unitary structure. After the bobbin thus far formed has undergone its final compression under the influence of the plunger 50, the table 53, upon two successive intermittent operations, is so positioned as to bring the bushing carrying the compressed material, into registration with the plunger 51 which is of a construction similar to that indicated by the numeral 50 and functions to extract the bobbin from the machine.

Directly beneath the rotating table 53 there is arranged an abutment 82 provided with radiating arms 83 which carry at their ends adjustable plungers 84 supported directly upon vertically adjustable screw threaded inserts 85. These plungers, it will be noted, are so arranged as to register with the plungers 24, 49 and 50, respectively, and

function as abutments or closures for the lower ends of the bushings 78. It will be noted too that since no abutment is provided for the plunger 48 this plunger will effect but little compressing influence upon the depolarizing mass, and that in the absence of such an abutment the previously compressed material will be slightly ejected from the bushing 78 leaving a predetermined quantity of the material of a given density within the bushing, the excess or protruding portion being thereafter scraped off by means of a scraper 86 carried by the abutment head 82 and positioned intermediate the plungers 48 and 49.

The electrode selecting and feeding mechanism 80 is supported by a suitable bracket 87 carried by the frame 9, and comprises a hopper 88 within the lower portion of which is journaled a star wheel 89 adapted to be operated through the instrumentality of a ratchet wheel 90, and a pawl 91 adapted to engage and intermittently rotate the same. This pawl is provided with a lug or pin 92 and is normally held in a retracted position by means of a tension spring 93, the pin being adapted to be engaged and lifted through the instrumentality of a lug or bracket 94 carried by the compression head 25. As the compression head 25 is lifted and lowered the carbon electrodes 95 are successively transferred from the hopper 88 to an inclined shute 96, they being permitted to slide freely down the same and assume a position directly over the depolarizing mass into which the electrode is about to be inserted. After a given electrode has assumed its position directly over the depolarizing mass a rectifying lever or arm 97 pivotally connected to a bracket 98 is so moved under the influence of a tension spring 99 as to lift the selected electrode to a vertical position between a pair of guides 100, the rectifying arm being permitted to move under the influence of the spring 99 when disengaged from an operating cam 101 upon the downward movement of the compression head 25. It will be understood that when the compression head is raised the cam 101 cooperating with the rectifying lever 97 will move the same to its retracted position thus permitting the next succeeding electrode to move freely down the shute 96 over the electrode engaging finger 102 carried by the lower end of the rectifying arm 97, the electrode assuming such a position at the lower end of the shute with respect to the finger 102 that the same will be moved to a vertical position intermediate the guides 100 when the rectifying arm 97 is again moved under the influence of the tension spring 99.

The conveyor mechanism 8, hereinbefore mentioned, is adapted to transfer a predetermined quantity of the depolarizing material from the hopper or container 7 to the

hopper 79 and comprises a pair of sprockets 103 and 104 carried respectively by the frames 6 and 9. The driving sprocket 104 is adapted to receive its power of rotation 5 through the instrumentality of a pawl and ratchet mechanism indicated as a whole by the numeral 105 and clearly shown in Figure 11. This mechanism comprises a ratchet wheel 106 in proximity to which is journaled 10 an oscillating arm 107 carrying a pawl 108 adapted to successively engage the elongated segmental teeth 109 of the ratchet wheel 106. The pawl, upon movement in one direction, is adapted to lift a locking dog 110 from 15 engagement with a segmental tooth 109 and retain the same in its retracted position a sufficient length of time to permit the ratchet wheel 106, upon reverse movement of the arm 107, to move under the influence of the pawl 108 in an unobstructed manner. Upon completion of the movement of the pawl 108 subsequent to its lifting the dog 110 out of engagement with the ratchet wheel 106, the dog 110 is permitted to engage the next succeeding 20 tooth 109, thereby positively preventing undue movement of the sprockets 103 and 104 as a result of their momentum thus insuring proper registration of the several buckets 111 with the exit opening 112 of the container 7, 25 and a proper position of these buckets with respect to the hopper 79. The oscillating arm 107 carrying a pawl 108 is operated through the instrumentality of a pitman rod 113 pivotally connected to a bell crank lever 114 suitably journaled to the frame 9, and 30 operated through the instrumentality of a cam 115 carried by the shaft 40. The several buckets adapted to receive the carbonaceous or depolarizing material from the receptacle 7 are identical and are mounted upon platforms or supports 116 to which they are pivotally connected by means of ears or wings 117, the platforms being rigidly connected to a sprocket chain 118 operating 35 upon the sprockets 103 and 104. As the buckets 111 successively register with the exit opening 112 of the receptacle 7, a valve or door 119 operating within guides 120 is opened to permit the passage of a quantity 40 of material from the container into the hopper, after which the valve is closed and so maintained until the next succeeding bucket is brought into registration with the opening 112. The mechanism for effecting the opening 45 and closing of the door or valve 119 comprises a bell crank lever 121 carried by the frame 6 and pivotally connected to a pitman rod 122 which in turn is connected to an operating arm 123 pivotally connected to the 50 frame 9, the arm 123 being provided with a roller 124 adapted to engage the face of the cam 125 operated by the shaft 42 which functions to impart to the operating arm 123 an oscillatory movement thus effecting a reciprocal movement of the valve or door 55

119. As the buckets 111 are brought successively into registration with the hopper 79 it becomes necessary to move them to the position shown in Figure 5 in order to deposit the depolarizing mass into the hopper, 70 and to effect this movement I have provided a cam 126 provided with a hill and dale face 127 adapted to cooperate with a bell crank 128 pivotally connected to the frame 9 and in turn connected to a second bell crank lever 75 129 by means of an interposed link 130. The latter named bell crank lever is adapted to successively engage the buckets 111 and since the cam 126 is provided with an irregular face it is obvious that when these buckets 80 are tilted a vibrating movement is imparted to the same. During such movement the bucket is first thrust into engagement with a depending guard 131, carried by the frame 9 and provided with a shield 132 to direct 85 the material into the hopper 79, after which the hopper rebounds to the bell crank lever 129 and is again thrust into engagement with the guard 131, the vibratory movement being maintained so long as the cam 126 is in 90 engagement with the bell crank lever 128. When operation of the conveyor mechanism is resumed the bucket previously dumped is permitted to fall by its own weight to its normal position, in which position it is maintained by means of a guide rail 131' over 95 which the buckets are adapted to slide throughout a predetermined phase in the operation of the machine.

In order that the depolarizing material, 100 which is more or less sticky or gummy in its nature, may be shaken loose from the wall of the hopper 79 I have provided an agitating mechanism so arranged as to impart to the hopper a vertical vibratory movement. The mechanism for effecting this agitating action comprises a stationary sleeve 133 carried by the frame, the upper edge of which is serrated as shown at 134. This serrated edge is adapted to engage a plurality of pins 110 135 carried by a rotatable sleeve 136 which in turn is connected to the hopper 79. As the sleeve 136 carrying with it the hopper 79 is rotated, it is obvious that the hopper 79 is agitated by reason of the fact that the pins 135 engage the serrated face 134 of the stationary sleeve. In order that the hopper 79 may have a suitable bearing surface, I have provided a relatively long depending bearing 137 adapted to operate within the stationary sleeve 133. This bearing by reason of its length affords an adequate bearing for the hopper 79 notwithstanding the fact that it is subjected to both rotary and vibratory movement.

The material when transferred from the hopper 79 enters an elongated bushing 138 which functions to direct the material into the bushings 78 as a result of the action of the plunger 24. When the bushings 78 are 139 125

- brought successively into registration with the bushing 138 the material, being injected thereinto is compressed to a uniform or substantially uniform density by the plunger 24.
- 5 The means for effecting rotation of the hopper 79 comprises a grooved pulley 140 loosely mounted upon the shaft 42 and connected to a pulley 141 carried by the sleeve 136, the two pulleys being connected by means of a belt 142 and driven through the instrumentality of a belt 143 adapted for connection with a line shaft, not shown, to which the primary belt 13, hereinbefore mentioned, is also adapted to be connected.
- 10 Having thus described my invention I claim:
1. A bobbin making machine comprising a rotatable table having depolarizing material receiving pockets, means for intermittently rotating said table, means for depositing depolarizing material into said pockets successively, means for subjecting the material within said pockets to compression to reduce the same to a predetermined density, 20 means for thereafter removing all but a predetermined quantity of the material from said pockets successively, means for successively introducing electrodes into said depolarizing material, means for exerting a final compression influence upon said material whereby the same is intimately united with said electrodes, and means for thereafter successively ejecting the depolarizing material together with the electrodes from the machine.
- 25 2. A bobbin making machine comprising a rotatable table having depolarizing material receiving pockets, means operated in synchronism with said table for introducing depolarizing material into said pockets, means for subjecting the material within said pockets to compression to reduce the same to a predetermined density, means for removing all but a predetermined quantity of said material from said pockets in succession, means for successively introducing electrodes into said material, means for subjecting said material successively to a final compression influence, and means for thereafter ejecting said material from the machine.
- 30 3. A bobbin making machine comprising a rotatable table having depolarizing material receiving pockets, means operating in synchronism with said table for depositing depolarizing material into said pockets in succession, means for subjecting the material within said pockets to compression to reduce the same to a predetermined density, means for reducing the material within said pockets to a predetermined quantity, means for introducing electrodes into said pockets successively, means for thereafter subjecting the material carried within said pockets to final compression, and means for successively
4. A bobbin making machine comprising an intermittently actuated table having depolarizing material receiving pockets, means for compressing a quantity of depolarizing material into a relatively compact mass and for thereafter introducing predetermined quantities of said mass into said pockets in succession, means for reducing the material within said pockets to a predetermined density, means for reducing the compressed mass of material within said pockets to a predetermined quantity, means for thereafter successively introducing into the material a plurality of electrodes, means for exerting a final compression influence upon depolarizing material, and means for ejecting the compressed depolarizing material from the machine.
5. A bobbin making machine comprising a rotatable table having depolarizing material receiving pockets, means for initially compressing a quantity of depolarizing material into a relatively compact mass, means for introducing a predetermined portion of said compressed mass into said pockets in succession, means for reducing the material within said pockets to a predetermined density, means for reducing the material within said pockets to a given quantity, means for introducing into the depolarizing material a plurality of electrodes in succession, means for subjecting the depolarizing material within said pockets to a final compression influence, and means for finally ejecting the compressed material from the machine.
6. A bobbin making machine comprising a rotatable table having depolarizing material receiving pockets, means for intermittently rotating said table, means for introducing a quantity of depolarizing material into said pockets in succession, means for subjecting the material within said pockets to compression to reduce the same to a predetermined density, a reciprocatory compression head having plungers adapted respectively to partially project the material from the pockets to introduce electrodes into the depolarizing material and to thereafter eject the material together with the electrodes successively from the machine, and means for severing the projected portions of material successively prior to the introduction of electrodes.
7. A bobbin making machine comprising an intermittently rotatable table having a plurality of depolarizing material pockets, means for introducing a quantity of depolarizing material into said pockets in succession, a reciprocatory compression head adapted to cooperate with said table to reduce the depolarizing material of each pocket to a predetermined quantity, to there-

- after introduce an electrode into the predetermined quantity of material and finally eject the material together with the electrode from the machine.
- 5 8. A bobbin making machine comprising a rotatable table having depolarizing material receiving pockets, means for initially compressing a quantity of depolarizing material into a relatively compact mass and 10 thereafter introduce portions of the same into said pockets in succession, a reciprocatory compression head adapted to cooperate with said table and reduce the previously introduced material to predetermined quantities, successively introduce electrodes into the predetermined quantities of material, subject each quantity of material to a final compression influence and thereafter eject the material together with the electrodes 15 from the machine.
9. A bobbin making machine comprising a table having a plurality of depolarizing material receiving pockets formed therein, a hopper adapted to receive depolarizing material, a tamper adapted to cooperate with said hopper for compressing said material into a relatively compact mass and for successively introducing said material into said pockets, means for intermittently rotating said table, means for ejecting a portion of the material from said pockets, means for severing the ejected portions thereby reducing said material to a predetermined quantity, means for introducing an electrode into 30 said material, means for compressing the material into which the electrode has been introduced and means for finally ejecting from the machine the compressed material together with the electrode carried thereby.
- 40 10. A bobbin making machine comprising an intermittently rotatable table having depolarizing material receiving pockets, means for intermittently rotating said table, means tending to retard the rotation of said table, 45 means for locking said table in a fixed position, means for introducing a quantity of depolarizing material into said pockets in succession, means for projecting a portion of the material from said pockets, means for severing the projecting portions thereby reducing said material to a predetermined quantity, means for introducing an electrode into the material, means for compressing the material into intimate engagement 50 with the electrode, and means for finally ejecting the depolarizing mass together with the electrode from the machine.
11. A bobbin making machine comprising an intermittently rotatable table having depolarizing material receiving pockets, an agitating hopper adapted to receive depolarizing material and thereafter deposit the same into said pockets in succession, means for depositing quantities of depolarizing material into said hopper in succession, and

means for imparting to said hopper rotatable and reciprocatory movement.

12. A bobbin making machine comprising a rotatable table having depolarizing material receiving pockets, a hopper adapted to receive and transfer quantities of depolarizing material to said pockets in succession, means for imparting to said hopper rotatable and reciprocatory movement and means for depositing quantities of depolarizing material into said hopper, the latter named means comprising an endless conveyor mechanism.

13. A bobbin making machine comprising a rotatable table having depolarizing material receiving pockets, a hopper adapted to receive depolarizing material and direct the same into said pockets in succession, a conveyor mechanism adapted to transfer to said hopper quantities of depolarizing material in succession, said conveyor mechanism being provided with a plurality of buckets, and means for progressively dumping said buckets and simultaneously imparting thereto an agitating movement.

14. A bobbin making machine comprising a rotatable table having depolarizing material receiving pockets, a hopper adapted to receive depolarizing material and direct the same into said pockets in succession, a conveyor mechanism adapted to transfer to said hopper quantities of depolarizing material in succession, said conveyor mechanism being provided with a plurality of buckets, and means for progressively dumping said buckets and simultaneously imparting thereto an agitating movement, the latter named means comprising a bucket engaging arm and a cam having a serrated face adapted to cooperate with said arm to impart thereto oscillatory movement.

15. A bobbin making machine comprising a rotatable table having depolarizing material receiving pockets, a hopper adapted to receive depolarizing material and direct the same into said pockets in succession, a conveyor mechanism adapted to transfer to said hopper quantities of depolarizing material in succession, said conveyor mechanism being provided with a plurality of buckets, means for progressively dumping said buckets and simultaneously imparting thereto an agitating movement, the latter named means comprising a bucket engaging arm and a cam having a serrated face adapted to cooperate with said arm to impart thereto oscillatory movement, and means adapted to cooperate with said buckets to direct the material into said hopper.

16. A bobbin making machine comprising a rotatable table having depolarizing material receiving pockets, a hopper adapted to receive quantities of depolarizing material and direct the same into said pockets in succession, a transfer mechanism adapted to

convey quantities of material to said hopper, said mechanism including a plurality of buckets, means for actuating said mechanism whereby said buckets are brought successively into dumping position with respect to said hopper, means for so moving said buckets when brought into dumping position with respect to said hopper as to deposit said material into said hopper, means for intermittently actuating said conveyor mechanism, and means adapted to cooperate with said actuating means for so locking said conveyor mechanism that said buckets are maintained successively in dumping positions with respect to said hopper for a predetermined length of time.

17. A bobbin making machine comprising an intermittently rotatable table having depolarizing material receiving pockets, means for intermittently rotating said table, a hopper adapted to direct depolarizing material into said pockets in succession, means for imparting to said hopper an agitating movement, a yieldable tamper adapted to cooperate with said hopper to facilitate the introduction of depolarizing material into said pockets in a relatively compact mass, means for projecting a portion of the mass of material from each of said pockets, means for severing the projecting portion to reduce the material to a predetermined quantity, means for introducing electrodes into said pockets in succession, means for compressing said material into a compact form around said electrodes, and means for ejecting the material together with the electrodes from the machine.

18. A bobbin making machine comprising an intermittently rotatable table having depolarizing material receiving pockets, means for intermittently rotating said table, a hopper adapted to direct the depolarizing material into said pockets in succession, means for imparting to said hopper an agitating movement, a yieldable tamper adapted to cooperate with said hopper to facilitate the introduction of depolarizing material into said pockets in a relatively compact mass, means for projecting a portion of the mass of material from each of said pockets, means for severing the projecting portion to reduce the material to a predetermined quantity, means for introducing electrodes into said pockets in succession, means for compressing said material into a compact form around said electrodes, means for ejecting the material together with the electrodes from the machine, means for intermittently rotating said table, and means for locking said table in predetermined positions.

19. A bobbin making machine comprising a molding element having depolarizing ma-

terial receiving pockets, means for depositing depolarizing material into said pockets successively, means for subjecting the material within said pockets to compression to reduce the same to a predetermined density, means for thereafter ejecting a portion of the material from said pockets in succession, and means for severing the ejected portion of the material.

20. A bobbin making machine comprising a molding element having depolarizing material receiving pockets, means for depositing depolarizing material into said pockets successively, means for subjecting the material within said pockets to compression to reduce the same to a predetermined density, means for thereafter ejecting a portion of the material from said pockets successively, means for severing the ejected portions, and means for successively introducing electrodes into the material remaining within said pockets.

21. A bobbin making machine comprising a molding element having depolarizing material receiving pockets, means for depositing depolarizing material into said pockets successively, means for subjecting the material within said pockets to compression to reduce the same to a predetermined density, means for thereafter ejecting a portion of the material from said pockets successively, means for severing the ejected portions, means for successively introducing electrodes into the material remaining within said pockets, and means for thereafter successively ejecting the depolarizing material together with the electrodes from the machine.

22. A bobbin making machine comprising a molding element having depolarizing material receiving pockets, means for depositing depolarizing material into said pockets successively, means for subjecting the material within said pockets to compression to reduce the same to a predetermined density, means for thereafter ejecting a portion of the material from said pockets successively, means for severing the ejected portions, means for successively introducing electrodes into the material remaining within said pockets, means for exerting a final compression influence upon the material subsequently to the introduction of said electrodes whereby an intimate union is effected between each electrode and its depolarizing material, and means for thereafter successively ejecting the depolarizing material together with the electrodes from the machine.

In testimony whereof, I have affixed my signature to this specification.

OTTO KARL REINHARDT.
